[57] ABSTRACT

This invention relates to fire extinguishing systems and specifically pertains to a multiple valve distributor head for pressure actuated cartridges containing a fire extinguishing agent which protect a plurality of fire hazard areas through fixed pipe systems attached to the valves of the distributor head. The multiple valve distributor head permits the selective discharge of the entire contents of the cartridge through one valve into the fixed pipe fire system protecting one hazard area upon detection of a fire in that area, without unseating or opening valves leading to the fixed pipe systems of unaffected hazard areas. The multiple valve distributor head comprises a fitting for pressurized cartridges of fire extinguishing agent formed with a plurality of opposed laterally-extending bosses having openings communicating with an interior distribution cam chamber and counterboard and internally threaded at their outer ends to receive independently actuated valves which in turn are connected to fixed pipe fire systems through which the fire extinguishing agent is discharged.

MULTIPLE VALVE DISTRIBUTOR HEAD**BACKGROUND OF THE INVENTION****1. Field of the Invention**

This invention relates to fire extinguishers and is directed particularly to improvements in self-contained pressure actuated fire extinguishers of the type designed to protect a plurality of small areas where there may be danger of local fires such as record vaults, paint lockers, electrical junction boxes, exhaust hoods, deep fryers, portable generators and the like. Specifically this invention pertains to a multiple valve distributor head for pressure-actuated cartridges of fire extinguishing agents permitting the selective discharge of the contents of a cartridge through one valve into the fixed pipe fire system protecting one of a plurality of hazard areas.

In particular, this invention is an improvement over the multiple port distributor head used in the Thermally Actuated Fire Extinguisher disclosed in my U.S. Pat. No. 3,392,787 issued July 16, 1968.

2. Description of the Prior Art

My U.S. Pat. No. 3,392,787 disclosed a thermally activated fire extinguisher which included a multiple port distributor head having a mixing and/or distribution chamber to allow the distribution of the fire extinguishing medium to selected areas through fixed pipes utilizing four or more pipe attaching ports. In effect, this fire extinguisher has a multiple port distribution head which, upon activation, would distribute the fire extinguishing agent through all ports simultaneously and through a fixed pipe system to each area protected by the system.

Most fire extinguishing systems today used to protect more than one fire hazard area operate by splitting the supply of fire extinguishing agent in approximately equal parts for each hazard area through the use of an in-line pipe tee or other supply splitting device which is part of the single fixed pipe fire extinguisher system. Such a system, however, simply divides the supply of fire extinguishing medium from a single cartridge, tank or supply source into smaller quantities, each of which must be sufficient to protect the greatest single hazard to which these smaller supplies are diverted. Therefore, individual hazards protected by a present multiple or split protection system, must be smaller than any single hazard which could be protected by a system designed to use the entire supply of fire extinguishing agent contained in the supply tank by the same inverse proportion as the number of times the tank is split or divided. Thus if a cartridge or tank contained 800 pounds of fire extinguishing agent and the fixed pipe system fully protected four areas, each area could not require or receive more than 200 pounds. Such systems result in a very expensive cost for minimal protection.

A further disadvantage of the present multiple hazard systems is the fact that all hazards protected by the system will receive some fire extinguishing agent even if the system is activated by a fire in only one of the hazard areas. This results in an inefficient utilization of expensive fire extinguishing agents and causes most of the fire extinguishing agent to be discharged in non-affected hazard areas. One such system which is commercially available utilizes a selector valve manifold which is connected to a single stationary fire extinguisher or source of fire extinguishing agent. A number

of fixed pipe and nozzle systems may be connected to such a selector valve manifold. A release mechanism, activated by a fire detection means within a hazard area causes only the valve for the piping system serving that particular affected area to open and hence distributes the fire extinguishing agent only to that area.

The present invention is directed to a further simplification of such a system. Rather than use the selector valve manifold and its complex piping system, it utilizes the multiple port distributor head disclosed in U.S. Pat. No. 3,392,787, modified to include valves and release mechanisms to control the opening of each port of the distributor head. Such a multiple valve distributor head may contain two or more valves each of which is connected to a port opening and each of which when activated will allow the selective discharge of the fire extinguishing agent from a cartridge tank or supply source to a particular fixed pipe system serving a single fire hazard area without opening the other valves of the multiple valve distributor head.

Hence, the principle object of this invention is to provide a multiple valve distribution head for fire extinguishing systems which will selectively exhaust the fire extinguishing medium in a tank through one valve of said head into the fixed pipe fire extinguishing system connected to that valve.

Another object of this invention is to provide a means for opening each valve in the multiple valve distribution head selectively through a fire detection or sensing device of the fixed pipe fire extinguishing system connected to said valve.

A further object of this invention is to provide a convenient, economical means for utilization of a single source of supply of fire extinguishing agent for protection of a plurality of fire hazard areas, any one of which would fully exhaust said source of supply.

Other objects, features and advantages of my invention will be apparent from the following description when read with reference to the accompanying drawing.

SUMMARY OF THE INVENTION

This invention pertains to a multiple valve distributor head for a cartridge or tank of fire extinguishing agent which provides a means for delivering the full supply of said tank to one of a number of different fixed pipe fire protection systems, each of which protects one of a number of different fire hazard areas. The system includes a multiple port distributor head for a cartridge or tank of fire extinguishing agent having a mixing or distribution chamber. This multiple port head is attached to a pressureized cartridge or tank of fire extinguishing agent. A valve is connected to each port of the multiple port distributor head such that the valve can be selected or opened by a fire detection means serving a fixed pipe fire extinguishing system in a fire hazard area. Called a multiple valve distributor head, this invention permits one source of supply of fire extinguishing agent to serve a number of fire extinguishing systems, each of which can call upon the full contents of a tank of fire extinguishing agent through activation of the one valve to which it is connected while at the same time the other valves would remain closed, thus preventing the discharge of fire extinguishing agent into areas where it is not needed. Thus the fire extinguishing agent is only used by the fire protection system which needs it, while the other systems remain dormant.

The specific means utilized for opening a valve in the multiple valve distributor head may be any of a number of conventional means. The activation means, whether it be pneumatic, wire spring or electrical, would always include a manual release mechanism which could be activated near the valve itself or from within a remote protected fire hazard area. In any event the means for opening the valve would have to be compatible with the fire detection means in the protected hazard area.

All fire hazards to be protected with one single source of supply of fire extinguishing agent would have to be ones which can be protected with the same fire extinguishing agent. Whatever agent is in the tank will be delivered to a fire hazard area when the valve is opened.

The valve used could be a ball valve which is simply attached to the multiple port distributor head. The ball valve lends itself to a variety of actuating means. The ball valve is controlled by a lever such that the ball is in either the open or the closed position. A frangible disk is also a possible substitute for the ball valve.

The multiple valve distributor head of the present invention provides a simple and inexpensive means for protecting a number of hazard areas with a single tank of fire extinguishing agent. It is particularly useful and economical in the protection of multiple hazards which are physically separate from one another and where there is no danger of fire spreading from one to the other.

BRIEF DESCRIPTION OF THE DRAWING

FIG. 1 illustrates a front perspective view of the multiple valve distributor head of this invention attached to a container of fire extinguishing agent.

DESCRIPTION OF THE PREFERRED EMBODIMENT

Referring now to the drawing, wherein like reference numerals denote corresponding parts, FIG. 1 illustrates a preferred embodiment of my invention comprising generally a multiple port distributor head 10 essentially similar in design and construction to that described in my U.S. Pat. No. 3,392,787, removably attached to a pressurized container 12 of fire extinguishing agent. Distributor head 10 has a plurality of ports 14, which are opposed laterally extending bosses having openings communicating with the interior chamber of distributor head 10 at their inner ends and are counterbored and internally-threaded at their outer ends to receive valves 16 or fittings to which either valves 16 or caps 18 are attached. The fire extinguishing medium is discharged through an open valve 36, as is herein below more fully described.

A multiple valve distributor head 10 will in the usual applications have from two to eight ports 14, not all of which will be utilized in any one installation. Unutilized ports, such as those designated by the reference numerals 20 and 22, are closed by a nut 24, externally threaded, removably received in an unutilized port 20 and held in closed position by a washer 26.

A utilized port such as port 28 removably receives a small pipe 30 externally threaded at both ends as indicated at 32 and 34. A standard valve 36 having internally threaded fittings is removably attached to the outward extending end of pipe 30. As illustrated in FIG. 1, valve 36 is a ball valve, but other types of valves may be utilized for this purpose. The outwardly extending

fitting of ball valve 36 is adapted to removably receive nozzles or pipes to which nozzles are attached through which the fire extinguishing agent is discharged, as is herein below more fully described. Valve 36 has a handle 38 and a wire rope 46 attached to open valve 36 mechanically by means of a spring or other forcible means incorporated within the actuating device or device of the individual system. Valve 36 may be activated by any one of several means with the aid of a derby release, such as a rate of rise sensor, a smoke detector or electronic heat sensing device, a spring and fusible link or by remote hand pull. Valve 36 and its associated fittings are enclosed in a cylindrical housing 40 defining an open chamber 42 in which valve 36 and its associated fittings are received, and attached to multiple port distributor head 10 on one side. Distributor head 10 has a pressure gauge 44 conveniently located to monitor the pressure within its distribution chamber. It also has a schraeder valve stem 45 to pressurize the cylinder or tank 12.

In operation, a fire protection system, such as that for which multiple valve distributor head 10 is designed, would be designed to protect a plurality of fire hazard areas. For purposes of illustration, let us assume that six record vaults of approximately equal size are to be protected and that to extinguish a fire in any one of the six vaults would require no more than 100 pounds of a dry chemical or other agent to be completely extinguished. Let us further assume that these record vaults are not in close proximity to one another or are segregated by cement walls such that fire could not spread from one to the other. The fire protection system within each vault would employ a separate detection system, which could be any of several types such as a rate of rise sensor, a fusible link or an electronic heat sensing device; a fixed pipe distribution system with nozzles for distributing a fire extinguishing agent throughout the vault when a fire is detected by the sensor; and a supply of fire extinguishing agent under pressure, connected to both the sensor and the fixed pipe system. The multiple valve distributor head permits each of the fixed pipe distribution systems to be connected to the same source of supply which, since the probability of a fire occurring at the same time in two different vaults is minimal, need only contain 100 lbs. of fire extinguishing agent. In this example each of the six fixed pipe systems would be connected to one of the ports 14 of multiple port distributor head by means of a valve 36. The sensor for each area would be linked by a wire rope 46 to the means 38 for opening the valve 36 to which the fixed pipe system for that area is connected. Multiple port distributor head is attached to a single tank 12 containing enough fire extinguishing agent to extinguish completely a fire in any one of the six vaults. Unused ports 20, 22 on multiple port distributor head 10 would be capped by a washer 26 and nut 24. When a sensor in a protected vault detects a fire, it causes a valve 36 to open, permitting a discharge of fire extinguishing agent from tank 12 through valve 36 into the fixed pipe distribution system serving that vault only. Since only one valve 36 has been opened by the sensor system, the fire extinguishing agent will be directed through multiple valve distributor head 10 only to the fixed pipe system connected to said valve 36.

The multiple valve distributor head of the present invention results in a substantial savings in costs of fire extinguishing agent. By utilizing a single source of sup-

ply such as a tank of dry chemicals or other agents to protect a plurality of fire hazard areas the tank need only contain the amount of fire extinguishing agent required for full protection of the largest hazard. In practice from two to eight hazard areas would be connected to one source of supply. The maximum savings would be achieved if eight hazard areas, each of which requires the same amount or less of fire extinguishing agent, were connected to one tank through the multiple valve distributor head. In this situation the quantity of fire extinguishing agent required for protecting the eight areas would be one-eighth of that required to protect the same areas individually.

In addition the multiple valve distributor head represents a distinct savings over a simpler multiple port distributor head because the individually controlled valves prevent the discharge of fire extinguishing agent into a hazard area in which there is no fire. Also the same economy in utilization of a single source of supply is achieved since the earlier multiple port distributor head provided no means for closing ports to unaffected hazard areas.

Furthermore, a fire protection system utilizing the multiple valve distributor head is simpler and less expensive in construction than one utilizing a selector valve manifold and the associated piping. The multiple valve distributor head also occupies less space than a selector valve manifold system, making its installation more convenient in many locations.

While I have illustrated and described herein only one form in which my invention can conveniently be embodied in practice, it is to be understood that this form is presented by way of example only and not in a limiting sense. The invention, in brief, includes all the embodiments coming within the scope and spirit of the following claims.

I claim:

1. An improved multiple distributor head for a fire extinguishing system of the type having a cartridge containing a fire extinguishing agent under pressure, a multiple port distributor head having an interior mixing

chamber removably fitted to said cartridge and in communication therewith, conduit means in said multiple port distributor head and in communication therewith, conduit means in said multiple port distributor head and in communication with the interior mixing chamber thereof for discharging the fire extinguishing agent through exterior pipes in communication with said multiple port distributor head, wherein the improvement comprises:

10 a plurality of valves, each of which is removably connected to and in communication with a port of said multiple port distributor head; each of said valves connected to and in communication with a system of pipes for the distribution of said fire extinguishing agent to a specific hazard area;

15 a housing for each of said valves and its fittings attached on one end to said multiple port distributor head;

20 means located in each of said hazard areas to detect a fire and upon detection thereof in a specific hazard area to actuate remotely and selectively that valve connected to the pipes serving to distribute a fire extinguishing agent in said hazard area;

25 means to effect the discharge of the contents of said cartridge of fire extinguishing agent through said multiple port distributor head and said selectively opened valve, said means being actuated when at least one of said valves is opened.

2. The improved multiple valve distributor head as defined in claim 1 wherein the improvement further comprises:

30 manually controlled means for opening each of said valves selectively, and including means to effect the discharge of the contents of said cartridge when at least one of said valves is opened.

3. The improved multiple valve distributor head as defined in claim 2 wherein the improvement further comprises:

35 removable means for closing unutilized ports of said multiple valve distributor head.
